UNITED STATES PATENT OFFICE

FRANK L. DARLING, OF BALTIMORE, MARYLAND, ASSIGNOR TO CROWN CORK & SEAL COMPANY, INC., OF NEW YORK, N. Y., A CORPORATION OF NEW YORK

METHOD OF PACKAGING AND APPARATUS THEREFOR

Application filed April 2, 1930. Serial No. 440,879.

This invention relates to a method of packaging and to apparatus therefor.

Many products, more particularly food products, are now packed in glass and the 5 receptacles sealed with caps such for example, as the well-known crown type which has an interior cushion disc of cork or similar material. This and similar caps cooperate with the edge or lip of the bottle around its 10 mouth, and this edge constitutes a sealing lip which coats with the cushion material of the cap. During the filling operation, there is apt to be considerable dripping or spilling of the product onto the receptacle including 15 the sealing lip thereof. This results in an unsatisfactory condition. If the product is of a syrupy or sticky nature, it often happens that the cap becomes, in time, so firmly stuck in place that it is almost impossible to remove it. If the product is of such character that seeds or other gritting matter adhere 20 to the lip of the receptacle, under the cap, such gritty matter often becomes embedded in the sealing gasket. This may prevent a 25 proper seal and result in a "leaker." Moreover, when the cap is removed the condition of the receptacle mouth is often somewhat foul and so objectionable to the consumer.

It has been proposed to wash the receptacles after capping. Such washing serves 30 to clean the necks and bodies of the receptacles but it does not remedy the condition referred to, because the lip and shoulder of the receptacle, being covered by the cap, are not 35 affected.

It is an object of the present invention to provide a method of packaging such that "leakers" and unclean packages are avoided. It is a further object of the invention to 40 provide an apparatus for effectively carrying out at least a portion of such method.

With these general objects in view, the invention consists in the method, features, combinations, details of construction and arrangements of parts which will first be described in connection with the accompanying drawings and then more particularly pointed out.

In the drawings:

50 Figure 1 is a view, partly in elevation and

partly in vertical section, of apparatus constructed in accordance with the invention;

Figure 2 is a sectional view taken on the line 2—2 of Figure 1; and

Figure 3 is a detail view showing part of 55 Figure 1 enlarged.

In carrying out the method of the invention, the receptacle is filled with its charge in any suitable manner, filling methods and machines being well known. The mouth of 60 the receptacle is then closed temporarily in such a manner as to form a substantial seal for the contents but to leave the sealing lip of the receptacle exposed. This may be accomplished for example, by a wedge-shaped 65 plug, such as illustrated in the drawings and hereinafter described. The sealing lip and rim of the receptacle mouth are then left exposed and may be cleaned, for example, by washing, thereby to remove any adhering 70 product received during filling. This may be accomplished in any suitable manner, for example, by subjecting the lip to water jets as hereinafter described.

After cleaning, the temporary closure is 75 removed and the permanent closure, e. g., a crown cork, may be applied in the usual manner.

The drawings show an apparatus capable 80 of carrying out part of the method described and forming, in itself, part of the invention.

Referring to the drawings, there is provided a temporary closure for a receptacle and means for applying and removing the same. This may be accomplished, for example, by mounting the closure on a head and causing relative movement between the head and the supported receptacle. In the embodiment of the invention here illustrated as an example, the receptacle 5 is supported 85 on a stationary table 6. Reciprocating to and from the supported receptacle is a bell-shaped head 7. Carried by the head is a wedge-shaped plug 8, of rubber or other suitable material, capacititated to enter the mouth of the receptacle but to leave the lip exposed. The plug 8 is secured to a carrier 9 which floats in a recess 10 in the head. The carrier 95 is impelled downwardly by a coil spring 100

11 and its normal position is fixed by a stop collar 12.

The stroke of the head and the relative position of the support are fixed for receptacles 5 of a given standard size, e. g., pints. When the head makes its down stroke, the plug enters the mouth of the receptacle and is checked, carrier 9 backing up against the spring until the plug is firmly wedged in 10 place. Receptacles of a given standard size may have minor variations in height. The apparatus is designed for the minimum height of the standard size and any over-height in receptacles is compensated for by 15 additional compression of spring 11.

The machine may be accommodated to receptacles of different standard sizes by changing the stroke of the head, or the relative position of the support, or both. For 20 receptacles having different mouth diameters, plug 8 may be removed and a similar plug of different size substituted.

While the head 7 may be reciprocated in any suitable manner, in the embodiment here 25 illustrated as an example, the head is secured by a nut 14 to a tube 15. This tube is connected by an arm 16, with a plunger 17 reciprocable in a frame bearing 18. On the lower end of plunger 17 is a cam roller 19 30 riding on a cam 20. This cam is mounted on a rotary shaft 21 to which power may be applied in any suitable manner. Cam 20 is laid out to cause a given reciprocation of plunger 18 with a dwell at the end of the 35 down stroke, whereby the head dwells in receptacle closing position long enough to allow for the washing operation hereinafter described.

There is provided means for supplying 40 wash water to the lip of the receptacle and this may be accomplished by jets in the head, connected to a source of water supply. As here shown as an example, the head 7 is formed in two parts so related and assembled as to leave an annular channel 23. Extending inwardly from this channel are a plurality of diagonal bores 24 opening into the interior of the head and forming an annular row of jets. These jets, as appears in 45 Figure 3, are arranged to deliver streams or sprays of wash water onto the flat lip of the receptacle. Below this row of jets are three additional rows of similar jets 25, 26, 27, arranged to deliver streams or sprays in the 50 manner illustrated in Figure 3. As there indicated, these several streams or sprays overlap more or less, with the result that the entire area of the receptacle lip, rim and shoulder is subjected to a washing action.

60 Channel 23 opens into a chamber 30 in the upper part of the head and this chamber, in turn, communicates with tube 15. Tube 15 may be connected with any suitable source of wash water supply by means of a flexible 65 hose 31. Thus the course of the water is

down through tube 15 and chamber 30, thence into annular channel 23 and out through the several jets.

There is provided a valve for controlling the water flow and in structures embodying 70 the invention to what is now considered the best advantage, the valve is automatically operated in timed relation with the head movement so as to open only while the plug is in receptacle closing position. Although 75 capable of various constructions, in that here shown as an example, in chamber 30 is a conical valve seat 32 which receives a conical valve 33. This valve has a stem 34 extending downwardly through recess 10 to engage carrier 9. The valve is normally held closed by a coil spring 35 engaging a collar 36 on the valve stem 34. When the head descends, carrier 9 is checked by the engagement of plug 8 with the bottle. Because of the engagement of valve stem 34 with the carrier, the valve is also checked. As the head continues downward, in completing its stroke, valve seat 32 moves away from the valve. Thus, in effect, the valve is opened on the down stroke 80 of the head after the bottle mouth is closed.

The parts remain in this position while the cam "flat" is passing under the roller and during this dwell the flow of wash water 85 cleans the bottle lip and shoulder.

When the head starts its up-stroke, the plug remains in the receptacle until carrier 9 is picked up by stop collar 12, spring 11 re-expanding. Meanwhile, however, valve seat 32 has moved up into contact with valve 100 33. Thus the valve is closed while the receptacle is still plugged and is thereafter held closed by spring 35. As the head continues its up-stroke, plug 8 is withdrawn from the receptacle and the latter is ready for its 105 permanent cap.

With the method and apparatus described, the permanent receptacle seal is applied to a clean lip, regardless of any product that may drop or spill during filling. As a result, the various objectionable features above referred to are avoided.

What is claimed is:

1. The method of packaging food and similar products in vessels of the type having a 110 mouth provided with a narrow top surface around the mouth to form a sealing lip, comprising filling the receptacle, closing the mouth of the receptacle temporarily without abutting the top surface or sealing lip 115 around the mouth whereby to leave the sealing lip thereof entirely exposed, washing the lip while the receptacle is so temporarily closed, removing the temporary closure and applying a permanent closure.

2. In apparatus of the class described, and in combination, a support for a receptacle, a closure plug proportioned to fit inside the mouth of the receptacle without abutting the top surface around the mouth whereby to 130

- leave entirely exposed the vessel sealing lip, means for inserting said plug in the receptacle mouth to close the same, and means for supplying wash water to the receptacle lip while the receptacle is so closed. 5
3. In apparatus of the class described, and in combination, a support for a receptacle, a wedge-shaped closure plug proportioned to close the mouth of the receptacle without abutting the top surface of the vessel around the mouth whereby to leave the sealing lip entirely exposed, means for forcing the plug into the mouth of the receptacle and thereafter removing the same, and means for supplying wash water to the lip of the receptacle while said plug is in receptacle-closing position. 10
4. In apparatus of the class described, and in combination a receptacle support, a bell-shaped head, a closure plug carried by the head proportioned to close the mouth of a receptacle while leaving the sealing lip thereof exposed, means for causing relative movement of the support and head, thereby to cause the plug to be inserted in the mouth of the receptacle, the head having water-jet openings for supplying streams of wash water to the lip of the receptacle, and conduit means for connecting said openings with a source of wash water. 15
5. In apparatus of the class described, and in combination, a receptacle support, a bell-shaped head, a closure plug carried by the head proportioned to close the mouth of a receptacle while leaving the sealing lip thereof exposed, means for causing relative movement of the support and head, thereby to cause the plug to be inserted in the mouth of the receptacle, the head having water-jet openings for supplying streams of wash water to the lip of the receptacle, conduit means connecting said openings with a source of wash water, and automatically acting valve means for controlling the flow of wash water. 20
6. In apparatus of the class described, and in combination, a receptacle support, a bell-shaped head, a closure plug carried by the head proportioned to close the mouth of a receptacle while leaving the sealing lip thereof exposed, means for causing relative movement of the support and head, thereby to cause the plug to be inserted in the mouth of the receptacle, the head having water-jet openings for supplying streams of wash water to the lip of the receptacle, conduit means for connecting said openings with a source of wash water, a valve for controlling the flow of wash water, and means whereby the valve is automatically opened after the plug has been inserted. 25
7. In apparatus of the class described, and in combination, a receptacle support, a bell-shaped head, a closure plug carried by the head proportioned to close the mouth of the receptacle while leaving the sealing lip thereof exposed, means for causing relative movement of the support and head, thereby to cause the plug to be inserted in the mouth of the receptacle, and thereafter withdrawn, the head having water-jet openings for supplying streams of wash water to the lip of the receptacle, conduit means for connecting said openings with a source of wash water, a valve for controlling the flow of wash water, and means whereby the valve is opened after the plug is inserted and closed before the plug is withdrawn. 30
8. In apparatus of the class described, and in combination, a receptacle support, a movable head, a wedge-shaped closure plug carried by the head, the head having water-jet openings for supplying wash water to the lip of the receptacle, conduit means for connecting said openings with a source of wash water, a valve in said conduit means, means for reciprocating the head to and from the supported receptacle, whereby the plug is inserted in the mouth of the receptacle and thereafter withdrawn, and for effecting a dwell between the advance and withdrawal of the head, and means controlled by the movement of the head for opening and closing said valve. 35
9. In apparatus of the class described, and in combination, a receptacle support, a movable head, a wedge-shaped closure plug mounted in the head to float therein, a spring tending to hold the plug in normal position, means for moving the head toward the supported receptacle with a given stroke, whereby the plug is inserted in the mouth of the receptacle, the plug being checked, against spring pressure, during the latter part of the stroke of the head, the head having water-jet openings for supplying wash water to the lip of the receptacle, conduit means for connecting said openings with a source of wash water, a valve in said connection, and means for causing said valve to be opened by said checking of the plug. 40
10. In apparatus of the class described, and in combination, a support for a receptacle, a closure proportioned to close the mouth of the receptacle while leaving the sealing lip thereof exposed, means for effecting relative movement between the closure and receptacle support to close the receptacle mouth, and means for automatically supplying washing fluid to the receptacle lip when the receptacle is so closed. 45

In testimony whereof, I have hereunto set my hand.

FRANK L. DARLING.
